UNITED STATES PATENT OFFICE.

HARRY VANE AND NORMAN BRITTON, OF CINCINNATI, OHIO.

PORTRABLE STAIR-ROUTER.

1,318,622.

Specification of Letters Patent. Patented Oct. 14, 1919.

Application filed February 11, 1916. Serial No. 77,717.

To all whom it may concern:

Be it known that we, HARRY VANE and NORMAN BRITTON, citizens of United States, residing at Cincinnati, in the county of 5 Hamilton, and State of Ohio, have invented certain new and useful Improvements in Portable Stair-Routers; and we do hereby declare the following to be a full, clear, and exact description of the invention, such as 10 will enable others skilled in the art to which it appertains to make and use the same.

The invention relates to a portable stair router.

The object of the present invention is to 15 provide a simple, practical and comparatively inexpensive stair routing machine adapted to be readily clamped to a stair stringer or other piece of timber and capable of accurately grooving the same across the 20 grain for providing grooves in stringers for steps and risers and various other purposes.

A further object of the invention is to 25 provide a portable stair routing machine of this character equipped with means for automatically feeding a cutter and for also 30 automatically stopping the feed of the machine at a predetermined point so that a plurality of similar grooves may be cut with accuracy.

With these and other objects in view the 35 invention consists in the construction and novel combination and arrangement of parts hereinafter fully described, illustrated in the accompanying drawings and pointed 40 out in the claims hereto appended, it being understood that various changes in the form, proportion and minor details of construction may be resorted to without departing from the spirit or sacrificing any of the advantages of the invention.

In the drawings

Figure 1 is a front elevation of a portable stair router constructed in accordance with this invention,

Fig. 2 is an end elevation of the same, Fig. 3 is a rear elevation of the stair routing machine,

Fig. 4 is a plan view of the same,

Fig. 5 is an enlarged horizontal sectional 50 view of a portion of the machine, illustrating the construction of the feed mechanism and the automatic stop,

Fig. 6 is a detail perspective view of the automatic stop,

Fig. 7 is a detail sectional view illustrating the construction of the operating shaft, 55

Fig. 8 is a detail sectional view illustrating the construction of the cutter.

Like numerals of reference designate corresponding parts in the several figures of 60 the drawings.

In the accompanying drawings in which is illustrated the preferred embodiment of the invention, the portable stair routing machine comprises in its construction a bed 65 plate 1 provided at opposite sides with grooves 2 for the reception of a base 3 of a supporting frame 4 slidable longitudinally of the bed plate and interlocked with the side grooves of the same. The side 70 grooves are preferably formed by vertical and inwardly extending flanges as clearly illustrated in Fig. 2 of the drawings.

The bed plate is provided at its end portions with longitudinal slots 5 having enlarged inner ends 6 to admit the heads of screws 7 of clamps 8 of approximately L-shape which are adapted to engage the stringer 9 of steps for securing the routing machine thereto. The clamps are adjustable 80 along the slot to arrange them in proper position for engaging a stringer or other timber.

The supporting frame 4 is preferably in the form of a vertical standard provided 85 with upper and lower forwardly projecting bearing arms 10 and 11 in which is mounted a vertical cutter shaft 12 having a threaded lower portion 13 for the reception of a cutter 14 consisting of spaced blades and a connecting head or portion and provided with a threaded opening to receive the threaded portion of the cutter shaft. The cutter which is adapted to be arranged at different elevations to vary the depth of the grooves 90 is spaced from the shoulder 15 by one or more washers 16 and is preferably clamped in its adjustment by set screws 17. Cutters of various sizes and styles may of course 95 be employed and the width of the grooves 100 may be varied by varying the size of the cutter. The cutter shaft is equipped at its upper end with a balance or fly wheel 18 and it is held against vertical movement in the bearing arms by an upper set collar 19 and 105 at its lower end a bevel pinion 20 having a set screw 21. The bevel pinion 20 which is horizontally disposed meshes with a ver-

tically disposed bevel gear wheel 22 mounted on a stub shaft 23 and provided with a pinion 24 which meshes with a pinion 25 that is also mounted on a suitable stub shaft. The upper pinion 25 meshes with a spur gear wheel 26 disposed vertically in the plane of the said pinions 24 and 25 and mounted on the front end of a horizontal operating shaft 27, journaled in suitable bearings of the supporting frame and extending rearwardly therefrom and equipped with a crank handle 28 by means of which the portable stair router is operated, but any other suitable operating device 15 may of course be employed. The train of gears for transmitting motion from the operating shaft to the cutter shaft may be of any desired size to secure the desired speed of the cutter shaft.

20 The operating shaft is also provided with a worm 29 which meshes with a horizontal worm wheel 30 of a vertical shaft 31 journaled in suitable bearings in arms 32 of a bracket 33 which is secured to the rear side 25 of the standard, but any other suitable supporting means for the vertical shaft of the feeding mechanism may of course be employed. The vertical shaft 31 constitutes a pivot for a horizontally disposed lever 34 extending longitudinally of the machine in the direction of the cut and carrying a plurality of gears 35, 36, 37 which mesh with one another. The inner gear 35 is mounted on the vertical shaft 31 and it is keyed or 35 otherwise secured to the same and it meshes with the intermediate gear 36 which is mounted on a vertical shaft or pivot 38 carried by the lever. The outer pinion 37 meshes with a longitudinal rack bar 39 located above the plane of the bed plate and supported by arms 40 extending upwardly from the bed plate at the rear side thereof. The lever is adapted to swing toward and from the rack bar and it is urged toward 45 the rack bar by a spring 41 consisting of a pair of arms and a connecting coil 42 which is arranged on the vertical shaft 31. One of the arms of the spring bears against the standard and the other engages a rod or 50 member 43 extending upwardly from the pivot 44 of the outer gear 37 and adapted to form a convenient handle or grip for swinging the lever away from the rack bar to permit the supporting frame to be moved 55 along the bed plate in returning the mechanism for another cutting operation. The gear 37 is automatically moved out of engagement with the rack bar to stop the feeding of the machine by a stop 45 consisting of 60 a yoke straddling the rack bar and having a clamping screw 46. The inner side of the yoke is beveled at 47 and the terminal 48 of the lever is slightly curved and it presents a rounded face to the automatic stop 65 to enable the lever to slide over the bevel

portion of the stop and swing the said gear wheel out of engagement with the rack bar. The automatic stop is adapted to be set at different points along the rack bar and it is equipped with a gage consisting of a horizontally disposed rod 49 carrying a block 50 in which a vertically disposed rod 51 is mounted. The block is equipped with set screws 52 and 53 for engaging the horizontal and vertically disposed rods and it has 70 bores or openings 55 and 56 adjustably receiving the said rods. The block is adapted to slide inwardly and outwardly on the horizontally disposed rod and the vertically disposed rod is movable upwardly and 75 downwardly and it may be arranged at different angles or inclinations as will be readily apparent. The bed plate is also provided with spaced line gages 56' of approximately L-shape adjustably secured in 80 bores or openings 57 by set screws 58. The line gages coact with engaging lines previously made on a stringer or timber to enable the machine to be properly positioned on a stringer or timber and the stop will 85 enable the feeding of the machine to be stopped at the desired point. While the machine is designed particularly for routing grooves for steps and risers where the grooves do not extend entirely across the 90 timber it may of course be advantageously employed for analogous operations and will cut entirely across a timber within its capacity or terminate the groove at any desired point between the side edges of the 95 timber.

What is claimed is:—

1. A portable routing machine including a bed, a standard slidably mounted on the bed, a cutter shaft carried by the standard, 105 an operating shaft carried by the standard and having connection with said cutter shaft, a feed shaft carried by the standard and having connection with said operating shaft, a rack bar carried by the bed, a lever pivoted to said shaft, a train of gears mounted on said lever and having connection with said rack bar, one of said gears being keyed to said feed shaft, and a stop mounted on said rack bar and adapted for 110 disengaging said train of gears with said rack bar, the adjacent faces of said stop and said lever being provided with coacting inclines.

2. A portable routing machine including 120 a bed, a standard slidably mounted on the bed, a cutter shaft carried by the standard, an operating shaft carried by the standard and having connection with said cutter shaft, a feed shaft carried by the standard and having connection with said operating shaft, a rack bar carried by the bed, a lever pivoted to said shaft, a train of gears mounted on said lever and having connection with said rack bar, one of said gears 125 130

being keyed to said feed shaft, a stop mounted on said rack bar and adapted for disengaging said train of gears with said rack bar, and a coil spring having arms engaging said standard and the shaft of one of said gears for normally retaining said train of gears in engagement with said rack bar.

In testimony whereof we affix our signatures in presence of two witnesses.

HARRY VANE,
NORMAN BRITTON.
